UNITED STATES PATENT OFFICE.

ABRAHAM O. FRICK, OF WAYNESBOROUGH, PENNSYLVANIA.

STEAM-BOILER.

SPECIFICATION forming part of Letters Patent No. 331,488, dated December 1, 1885.

Application filed May 9, 1885. Serial No. 164,923. (No model.)

To all whom it may concern:

Be it known that I, ABRAHAM O. FRICK, a citizen of the United States, residing at Waynesborough, in the county of Franklin 5 and State of Pennsylvania, have invented certain new and useful Improvements in Steam-Boilers; and I do hereby declare the following to be a full, clear, and exact description of the invention, such as will enable others 10 skilled in the art to which it appertains to make and use the same.

This invention relates to the type of steam-boilers provided with so-called "steam-separators."

15 My invention, though adapted to various styles of boilers, is more especially designed for use on traction-engine boilers, the object being to so construct and apply the separator or steam-drum that a higher water-level can 20 be maintained than in the ordinary traction-engine boilers, and the crown-sheet kept covered with water in traveling down descending grades without danger of priming.

To this end my invention consists, first, in 25 arranging a steam-drum in the upper part of the boiler, having an open neck extending up into the steam-dome; and, secondly, in providing this steam-drum with an open-ended elevated pipe at the fire-box end of the boiler, 30 so that while steam generated around the fire-box may continue to flow through this pipe into the steam-drum when the dome is sealed by water in descending a hill, but little or no water can find its way into the steam-drum 35 through this pipe when the boiler is tilted the other way in ascending a hill.

In order that my invention may be clearly understood, I have illustrated in the annexed drawings, and will proceed to describe, a practical form thereof.

40 Figure 1 represents a vertical axial section of a locomotive or traction engine boiler containing my improvement. Fig. 2 represents a transverse section thereof, taken in the plane 45 of broken line xx of Fig. 1. Fig. 3 illustrates a modification.

The same letters of reference indicate identical parts in all the figures.

The general construction of the steam-boiler 50 illustrated in the annexed drawings is like that of an ordinary multiflue traction-engine boiler of the locomotive-boiler type. A re-

fers to the steam-drum, the cross-sectional contour of which follows that of the space above the boiler-flues, it being, however, somewhat 55 smaller than said space, so as to permit free circulation of water and steam all around it. The length of the steam-drum is nearly co-extensive with the length of the flues, and it is so arranged in the boiler as to reach from near 60 the back of the fire-box to near the flue-sheet at the front end of the boiler; but it may be extended over the fire-box, as indicated by dotted lines in Fig. 3. This steam-drum has an upright neck, A', open at the top and projecting up into the steam-dome to such height 65 as to prevent water from flowing over into it under any position that the boiler can assume in practical work. Steam is drawn from the steam-drum through the steam-pipe B, inserted 70 through the top of the steam-dome, and reaching deep down into the steam-drum, so that the generated steam has to descend to near the bottom of the steam-drum before it can flow into pipe B. In this descending flow the water 75 carried in suspension by the steam will be precipitated to a greater or less extent. The steam-drum is supported by cross-bars $a a$, which are riveted to the boiler-shell. Any other convenient or preferred means may be 80 employed for supporting it and holding it in position.

The steam-drum is constructed with watertight heads, but it is provided with an open-ended pipe, C, which projects through one of 85 the heads into the space above the fire-box to near the front side thereof, occupying the highest parts of the steam-drum and boiler, as clearly shown in Fig. 1. The pipe C extends far into the steam-drum and up to about 90 the center of its upright neck A'. The exterior end of the pipe may have an upward bend, so as to run its end close up to the shell of the boiler, as shown. The pipe should be suitably fastened. This pipe C affords a direct passage to the interior of the steam-drum for steam generated at the fire-box end of the boiler even when the boiler is tilted so that the water seals the dome; but by reason of its length both inside and outside of the steam-drum 95 and its elevation this pipe can conduct but little water into the steam-drum, even when the boiler is tilted so far in the other direction that the water-level rises above the exte-

rior end of the pipe, because then the interior end of the pipe assumes a position above the water-level. This is illustrated by the line *z z* on Fig. 1, which line is assumed to indicate the water-line in the boiler on ascending a steep hill, and shows that the water cannot run out of the service-pipe and into the steam-drum. It will be observed that this could not be prevented if the separator-pipe were not extended far into the steam-drum. The line *w w* is assumed to indicate the water in the boiler on descending a steep hill. Whatever water may enter the steam-drum through pipe C will be quickly evaporated. However, a blow-off pipe, D, is provided, by means of which the water, as well as sediments, can be blown out of the steam-drum at any time. The interior end of the pipe C, which I term the "separator-pipe" for the sake of distinction, may be turned up into the neck A', forming either an elbow or a goose-neck overhanging the upper end of said neck, as respectively indicated by dotted lines in Figs. 1 and 2, so that any water entering the pipe may be blown out by the steam when the boiler assumes a more level position, and thus prevented from entering the steam-drum at all. The form of the steam-drum will vary with the style of the boiler, and the form and arrangement of the separator-pipe may also be considerably varied to suit circumstances and the views of boiler-makers. The steam-service pipe B may also be arranged differently; but in all cases it must take the steam from the steam-drum.

Fig. 3 illustrates a modification of the separator-pipe, it being in this case a mere upright nozzle projecting from the steam-drum

up into a secondary steam-dome at the fire-box end of the boiler. In this construction no water can flow from the water-space of the boiler into the steam-drum under any possible position of the boiler in practical work.

It will be readily observed that the steam-drum arranged in the upper part of the boiler acts not only as a steam-separator, but also as a displacement tank or drum, which takes up so much room beyond the crown-sheet of the fire-box as to prevent the water-line from falling below the crown-sheet when the boiler is tilted in descending a hill, which is a very important consideration in traction-engine boilers.

I claim as my invention—

1. The combination, substantially as before set forth, of a steam-boiler of the locomotive-boiler type, the steam and displacement drum in the upper part thereof, having an open neck projecting up into the steam-dome, and the separator-pipe for conducting steam into said drum from the space above the crown-sheet.

2. The combination, substantially as before set forth, of a steam-boiler of the locomotive-boiler type, the steam and displacement drum in the upper part thereof, having an open neck projecting up into the steam-dome, the separator-pipe for conducting steam into said drum from the space above the crown-sheet, and the steam-service pipe projecting into said drum.

In testimony whereof I affix my signature in presence of two witnesses.

ABRAHAM O. FRICK.
